UNITED STATES PATENT OFFICE.

ALONZO W. ALLEN, OF STREATOR, ILLINOIS, ASSIGNOR OF ONE-HALF TO EMANUEL M. DAVIS, OF STREATOR, ILLINOIS.

ARCOGRAPH.

1,146,607.

Specification of Letters Patent. Patented July 13, 1915.

Application filed March 21, 1914. Serial No. 826,291.

To all whom it may concern:

Be it known that I, ALONZO W. ALLEN, citizen of the United States, residing at Streator, in the county of La Salle and State of Illinois, have invented new and useful Improvements in Arcographs, of which the following is a specification.

My present invention pertains to "arcographs", and is designed more particularly 10 as an improvement on the "arcograph" constituting the subject of my Letters-Patent Number 915,926, dated March 23, 1909.

The object of the present invention is to provide an "arcograph" having such capacity that its arms are adapted to swing or turn both ways from a straight line, this with a view to using the device for the drawing of reverse curves without the necessity of changing the position of the instrument. In 20 other words curves can be drawn in either direction close to a wall provided the table is fastened to a side wall.

A secondary object of the invention is the provision of an "arcograph" with which 25 may be used any pencil or drawing pen thereby doing away with the necessity of an appliance for holding a pen or pencil as in my before mentioned Letters-Patent.

The invention further contemplates the 30 provision of an "arcograph" in which the guides can be adjusted in such manner as to avoid marring of the table, this being feasible inasmuch as the weight of the instrument tends to assist in holding the same in 35 position.

Another advantageous feature of the invention is the construction which permits of the "arcograph" being folded into small compass.

With the foregoing in mind the invention 40 will be fully understood from the following description and claims when the same are read in connection with the drawings, accompanying and forming part of this specification, in which:

Figure 1 is a plan view illustrating the three members of my novel instrument as the same appear when properly arranged in the first instance relative to a cord line 50 from which the arc of a circle is to be drawn. Fig. 2 is a detail section illustrative of the manner in which the arms are connected together and to the main stem. Fig. 3 is an enlarged section illustrative of the slidable member on the main stem. Fig. 4 is a trans-

verse section taken through one of the arms and showing the manner in which the index devices are mounted on the arms. Fig. 5 is an enlarged plan of one of the auxiliary members. Fig. 6 is a longitudinal section of 60 one of the auxiliary members or guides.

Similar numerals of reference designate corresponding parts in all of the views of the drawings.

Among other elements my improved device 65 comprises a main stem 1. This stem is provided with a graduated scale, and the said scale is numbered as shown in Fig. 1. At one end the scale is notched as indicated by 2 so as to form a guide for the pencil or 70 pen used in connection with the device.

Connected to the stem 1 and to each other in the manner shown in Fig. 2 are two arms 3. As will be readily observed the said connection is such that the arms may be expeditiously and easily adjustably fixed relative to each other and the stem 1; the connection comprising a threaded pintle 4 and a binding nut 5. On each of the arms 3 is a rail 6, of dove-tail form in cross-section, and on 80 the said rail is mounted an index device 7, equipped with a set screw 8.

Mounted to slide on the main stem 1 is a body 9, equipped with a set screw 10. The said body is provided with lateral projections 11, and pivotally connected to these 85 projections and also to the arms 3 are bars 12.

13—13 are the auxiliary members or guides of the device. These auxiliary members or guides are identical in construction 90 and therefore a detail description of the one shown in Figs. 5 and 6 will suffice to impart a definite understanding of both. As will be readily manifest the member referred to is provided at 14 with a screw threaded 95 pointed pin by which it may be adjustably fixed in position. The adjustable capacity of the said pin is advantageous inasmuch as it enables the pin to be set in such position as not to mar the board on which the device 100 is used.

By using my novel instrument or device compound curves such as used in laying out railways, can be readily drawn and nicely compounded, the mode of procedure 105 being as follows: It will be understood that when the apex of the angle is at the point of either auxiliary member or guide 13 that a line drawn with the arm is a tangent to the curve, and at right angles with the tangent 110

is a radial line. By extending the tangent to the left of the point and placing the left hand arm on this tangent and setting the angle so that the right hand arm will come 5 to any point, the curves will compound.

The indexes 7 are used to determine the positions of the guide members 13. This will be understood when it is stated that when the radius and degree of the arc to be 10 drawn are known, the length of the chord may be determined and the indexes set equidistantly from the bar 1 at a distance apart equal to the length of such chord and serve to indicate the proper positions of the members 13 in using the device.

Having described my invention, what I claim and desire to secure by Letters-Patent, is:

1. A device for the purpose described, 20 comprising a stem, arms pivotally connected together and to the stem, means whereby said arms can be accurately fixed in predetermined mathematically-correct positions relative to the stem, and indexes adjustable 25 on the arms in the direction of the length thereof.

2. A device for the purpose described, comprising a stem, arms pivotally connected together and to the stem, said arms having 30 rails of dove-tail form in cross-section, indexes adjustable on said rails, and means for 35 adjustably fixing the indexes to the rails.

3. In means for the purpose described, the combination of auxiliary members or 35 guides provided with means for holding them in position on a drawing surface, and a major member having arms capable of swinging in both directions from a straight

line and adapted to be set against said auxiliary members or guides and also having 40 indexes adjustable on the arms in the direction of the length thereof.

4. In means for the purpose described, the combination with auxiliary members or guides having points and also having means 45 for holding them in position on a drawing surface, of a major member comprising a stem having a notch in its forward end, arms pivotally connected together and to said stem at a point adjacent to the notched 50 end of the stem, and means for adjustably fixing the arms relative to each other and the stem.

5. In means for the purpose described, the combination with auxiliary members or 55 guides having points and also having means for holding them in position on a drawing surface, of a major member comprising a stem having a notch in its forward end and arms pivotally connected together and to 60 said stem at a common point adjacent to the notched end of the stem.

6. A device for the purpose described comprising a stem having a notch in its forward end, arms pivotally connected together 65 and to said stem at a common point adjacent to and in rear of the notched end of the stem, and means for adjustably fixing the arms relative to each other and the stem.

In testimony whereof I have hereunto set 70 my hand in presence of two subscribing witnesses.

ALONZO W. ALLEN.
